TABLE LAMP OR SIMILAR ARTICLE

William H. Green, 4921 Dodt Ave., New Orleans, La.

Filed Oct. 24, 1961, Ser. No. 67,234

Term of patent 14 years

(Cl. D48—20)

The top of the shade is open and conventional, and the side not shown is substantially the same in appearance as the side shown except for omission of the belt-like member.

I claim:

The ornamental design for a table lamp or similar article, as shown and described.
